UNITED STATES PATENT OFFICE.

WALLACE L. CLAY, OF THE UNITED STATES ARMY.

BULLET.

1,202,162.

Specification of Letters Patent.

Patented Oct. 24, 1916.

Application filed December 30, 1915. Serial No. 69,457.

To all whom it may concern:

Be it known that I, WALLACE L. CLAY, captain, United States Army, and a citizen of the United States, at present residing at 5 Philadelphia, in the county of Philadelphia and State of Pennsylvania, have invented certain new and useful Improvements in Bullets; and I do hereby declare the following to be a full, clear, and exact description 10 of the invention, such as will enable others skilled in the art to which it appertains to make and use the same.

This invention relates to bullets especially adapted for use in firearms, and has for its 15 object to improve the armor-piercing qualities of the bullets now in use, as well as to provide other useful features as will presently appear.

With these and other objects in view, the 20 invention consists in the novel details of construction and combinations of parts more fully hereinafter disclosed and particularly pointed out in the claims.

Referring to the accompanying drawings 25 forming a part of this specification in which like numerals designate like parts in all the views: Figure 1 is a diagrammatic plan view of the completed bullet; Fig. 2 is an enlarged sectional view of the preferred form 30 of the bullet; Fig. 3 is an enlarged sectional view of a somewhat modified form of bullet; and Fig. 4 is a plan view of the form shown in Fig. 3.

1 indicates any suitable outer jacket for 35 the bullet, but preferably made of cupro-nickel or what is known as gilding metal. In the regular service bullet at present employed by the United States Army, the jacket 1 is usually turned in as at 2 leaving 40 the unclosed space 3, and I have adopted this construction in the form shown in Fig. 2. Immediately inside the jacket 1 is an 45 envelop 4 of lead, a lead alloy or other relatively soft metal. The said envelop 4 is preferably thickened as it leaves the cylindrical portion of the jacket and I prefer to so dispose its material as to form the solid 50 nose 5 closely fitting the interior of the sharp nose 6 of the jacket 1. At the rear of 55 the bullet I likewise prefer to thicken the envelop 4 into the solid base portion 7. At the rear of the base portion 7, and between 60 said base portion and the turned in portion 2 of the jacket 1 I prefer to insert a steel 65 disk 8 which is conveniently made of a thickness of say one thirty-second of an inch.

On the interior of the envelop and between its members 5 and 7, I locate a solid steel 62 slug 10 which may be of any suitable shape and of any suitable kind of steel but I prefer to make it of hardened steel or of a hard 65 steel alloy, and to give it substantially the shape illustrated. I have found that the best results are produced by rounding its extreme point 11 substantially as shown. 68

The above bullet may be made of any suitable or desired dimensions, but I prefer to adopt the dimensions illustrated which are substantially the same as those now employed in connection with the regular army 70 bullet, and which therefore enables me to employ this bullet in the regular service rifles and machine guns.

Referring now to the modified form of the invention shown in Figs. 3 and 4, the construction varies from that above disclosed in that the outer jacket 15 is closed at the base 16, and it terminates at the point 18 which is somewhat short of the extreme 75 point 17 of the bullet. The lead or other 80 soft metal envelop 19 is thickened as at 20 to complete the profile of the sharp nose of the bullet, and it is also thickened as at 21 to fit the interior of the base 16 of the jacket 15. Inside the envelop 19 is placed the steel 85 slug 22 which is, or may be of substantially 90 the same dimensions and material as the slug 10 disclosed in connection with Fig. 2. I also prefer to make this bullet of substantially 95 the dimensions illustrated in connection with Fig. 3, in order that this form of the invention may be likewise used in connection with the regular service rifles and machine guns.

In the form shown in Fig. 2, I have found 95 that a convenient weight of the slug 10 is say 47 grains when the entire bullet weighs 150 grains, and I have further found in connection with the form of bullet illustrated in Fig. 3 that the slug 22 may weigh say 48 100 grains when the entire weight of the bullet is 150 grains.

It will thus be seen that in both forms of the invention, the extreme points 11 of the slugs 10 and 22 will upon impact, be supported by the lead or other relatively soft material surrounding the same, and that the said slugs will thereupon, when penetrating armor, act in a manner somewhat analogous to large projectiles which carry soft steel 110 caps surrounding their hardened armor-piercing points.

As a matter of fact, I recommend that the slugs be given a special heat treatment which will vary according to the kind of steel employed and which will serve to harden the point 11 to that degree which will be found most effective in practice.

In the form illustrated in Fig. 3, the extreme nose or point 11 being blunt, it will readily compress the solid mass 20 upon striking armor, said point will be therefore supported in the manner above explained and the jacket 15 being carried forward to the point 18, it will crimp inwardly into the lead or other soft material 19 in such a manner as to afford still further protection to the said point 11.

In the form shown in Fig. 2, the jacket 1 being extended to the extreme point 17 of the bullet, it of course crimps up with the lead and serves to confine the same around the slug 10 and thus aids in preventing the said slug from breaking up.

I have found by actual tests that in neither form of bullet do the slugs break up upon impact against hardened steel plates.

In both cases the thickened masses of soft material such as 7 and 21 are suitably supported from the jacket, and the energies pertaining to said masses are utilized in aiding the slugs to penetrate the target. The disposition of the metal is such that the ballistics of the bullet are not impaired even when the service dimensions are employed, and it therefore follows that the length of the bullet is not sufficient to prohibit it being used in machine guns.

Of course, the bullet can in all cases be made with or without a groove or cannelure into which the cartridge case can be crimped so as to prevent the escape of powder gases when fired. It will further be seen that the cost of manufacture need not be materially larger than the present regulation ammunition.

From actual tests made at varying ranges with this bullet, its accuracy and penetration have proved exceedingly satisfactory, and the steel disk 8 has been found very useful in increasing the penetration through hardened armor plates.

It is an important feature of the invention that in the form illustrated in Fig. 3, the extreme tapered portion of the bullet is not covered with a hard metal jacket because the above tests have shown that when the standard army jacket strikes at an angle, hardened armor plates, such as are ordinarily used on aeroplanes or as defenses

from rifle fire in trenches etc., the metal jacket with which the bullet is covered causes the latter to glance off and thereby fail to penetrate the armor. On the other hand, by leaving a portion of the extreme point of the bullet uncovered as is illustrated in Fig. 3, the soft metal of the envelop takes against the plate, arrests the bullet, so to speak, and enables a very much better penetration than it is possible to get where the entire point is covered with the jacket.

It is another important feature of the invention that by so disposing the metal as illustrated, the center of gravity of the system is maintained at about the same point as the center of gravity of the standard bullet and therefore all liability to tumble during flight is avoided. In fact I have found both the accuracy and the penetration of armor plates very satisfactory indeed up to as high as two thousand yards.

In no case are my bullets more than say one tenth of an inch longer than the regular service bullets and therefore they are readily adaptable for general use and in fact cartridges containing the same can be fed from the belts of machine guns.

It is evident that those skilled in the art may vary the details of construction as well as the arrangement of parts without departing from the spirit of the invention, and therefore I do not wish to be limited to the above disclosure except as may be required by the claims.

What I claim is:—

1. In a bullet for fire arms the combination of a steel slug provided with a rounded penetrating point; a mass of softer metal covering and extending forward of said point; a mass of softer metal located at the rear of said slug; and a metal jacket open at its front end inclosing said slug and masses of metal, substantially as described.

2. In a projectile the combination of a central pointed steel slug; a mass of softer metal located at the rear of said slug; a mass of softer metal located in front of and around the forward end of said slug; and a jacket covering said first named mass and a portion only of said last named mass, substantially as described.

In testimony whereof I affix my signature, in presence of two witnesses.

WALLACE L. CLAY.
